UNITED STATES PATENT OFFICE.

WILLIAM A. BLACK, OF ASHEVILLE, NORTH CAROLINA.

THERMOMETER HOLDER CASE.

1,405,709.

Specification of Letters Patent.

Patented Feb. 7, 1922.

Application filed October 11, 1920. Serial No. 416,136.

To all whom it may concern:

Be it known that I, WILLIAM A. BLACK, a citizen of the United States, residing at Asheville, in the county of Buncombe and 5 State of North Carolina, have invented certain new and useful Improvements in Thermometer Holder Cases, of which the following is a specification.

This invention relates to an improvement 10 in holders or cases for physicians' thermometers.

A primary object of the invention is to provide a device that permits of safely and conveniently carrying the thermometer in 15 the pocket or instrument case, and more especially to provide means for resetting the mercury of the thermometer without danger of breaking, and with a minimum physical exertion.

20 A further and more specific object is to provide an all metal device that is strictly sanitary, and of durable and lasting construction.

With the above and other objects in view, 25 which will more readily appear as the nature of the invention is better understood, the same consists in the novel construction, combination and arrangement of parts herein-after more fully described illustrated and 30 claimed.

A preferred and practical embodiment of the invention is shown in the accompanying drawings in which:

Figure 1 is a perspective view of the device, illustrating its use.

Figure 2 is an elevation thereof.

Figure 3 is a vertical sectional view on the line 3—3 of Figure 2.

Figure 4 is a cross sectional view on line 40 4—4 of Figure 2.

Similar reference characters designate corresponding parts throughout the several figures of the drawings.

In the embodiment of the invention shown 45 it will be seen that the same includes a handle member 1 which may be of transversely arched or channelled formation throughout the greater part of its length, but at one end flattens out as at 2 to facilitate the formation of the hinge knuckles 50 3, which cooperate with the mating knuckle portions 4 formed at one end of a tubular socket member or case carrier 5, to receive and hinge- 55 edly connecting the handle therewith.

The tubular socket member 5 above referred to is preferably cut away as indicated at 7 to provide free entrance for the tubular case C which holds the thermometer T, and its internal bore preferably tapers 60 or diminishes in diameter from the entrance end 7 toward the lower open end 8 to provide a relatively tight friction fit between the said case and the socket. The thermometer holding case C may be furnished 65 as a part of the device, or the usual metallic casing in which physicians' thermometers are sold may be readily used in place thereof, the socket member 5 being especially constructed with that end in view. As shown 70 in the drawings, the handle 1, by reason of its channelled or transversely arched formation may embrace the case C when the parts are brought into folded relation to permit of the device being readily carried 75 in the pocket. In other words the case or sheath for the thermometer may nest within the handle when the parts are folded to form a compact and conveniently carried device.

By reference to Figure 1 of the drawings 80 it is believed that the manner of using the device will be readily apparent. In the figure referred to it will be seen that the operator may grip the handle in such a manner as to leave the socket element 5 and 85 case C free to move about the pintle 6 of the hinge connection, so that upon swinging the end downwardly with a sharp quick movement, the socket member and case will be abruptly moved from the first dotted line 90 position to the final dotted line position, whereby the mercury in the thermometer will be reduced by centrifugal force and the abrupt or sharp jar produced at the end of each movement.

95 A distinctive feature of the invention is the provision of an all metallic device including handle and socket members connected by a hinge joint, the said socket member being open at both ends to receive and grip the casing which holds the thermometer. Another feature is the arrangement which permits of the portion of the casing that projects from the socket to nest in the handle.

100 Without further description it is thought that the many features and advantages of the invention will be readily apparent to those skilled in the art, and it will of course be understood that changes in the form, pro- 110

portion, and minor details of construction may be resorted to within the scope of the appended claims.

I claim:

- 5 1. A device of the class described including a thermometer casing receiving socket member opening at both ends and adapted to receive therein a thermometer casing, and a handle pivoted to the upper edge of the 10 socket member and adapted to receive the portion of the thermometer projecting below the socket member when the handle and casing are folded toward each other.
- 15 2. A device of the class described including a handle of channelled formation, a socket member hinged thereto, said socket member being of tubular formation and open at both ends, and adapted to receive therein a thermometer casing having one 20 end thereof projecting beyond said socket member to nest in the channelled portion

of the handle when the parts are brought into folded relation.

3. A device of the class described including a metallic handle of channelled formation throughout the greater portion of its length but flattened out at one end and formed with hinge knuckles, a socket member of tubular formation and open at both ends, and one of said ends being flattened 25 out and also formed with hinge knuckles matching with the hinge knuckles on the end of the handle, a pintle pin for said knuckles, and a thermometer holding casing adapted to be inserted in the socket 30 member.

In testimony whereof I hereunto affix my signature in the presence of two witnesses.

WM. A. BLACK.
